J. W. PARKS

SHIPPING CASE

Filed Nov. 15, 1923

UNITED STATES PATENT OFFICE.

JOSEPH W. PARKS, OF ALTOONA, PENNSYLVANIA.

SHIPPING CASE.

Application filed November 15, 1923. Serial No. 674,946.

This invention relates to shipping cases, which are used to ship small live stock and day old chicks, and has for its primary object a case of an improved corrugated paper type, in which either small live stock or day old chicks can safely be shipped without the usual loss which results from insufficient ventilation.

A further object of this invention is to provide a shipping case having a partition or a plurality of the same each of which is adapted to divide the case into separate compartments and to support the case lid with which the partition is designed to co-act. A still further object of this invention is to provide adequate means of protecting the ventilation holes provided in each case by a series of crimped paper ribs, which are adapted to be placed in the case cover, as well as on each side of the case and lid, which provision prevents in a very practical way the compactness of the cases and insufficient ventilation, where several cases are shipped together.

Another object of this invention is to provide the case cover with stiffening ribs positioned at right angles to each other, in such manner that the case cover can readily be tied in place on the case, with provision for attaching a case-lifting strap or similar means.

With these and many other objects in view, which will be more readily apparent as the nature of the invention is better understood, the same consists in the novel combination, construction and arrangement of parts as will be hereinafter fully pointed out, illustrated and claimed.

It will be quite readily understood by those skilled in the art to which invention belongs, that the same is quite susceptible of various changes and modifications without departing from spirit or scope of the invention, but a preferred and practical embodiment thereof is shown on the accompanying drawing, in which:—

Fig. 1 is a perspective view of my own shipping case, showing the lid in position together with the partition which co-acts with it.

Fig. 2 is a plan view of my improved case.

Fig. 3 is a side elevation of the parts shown in Figure 2 of the drawings.

Fig. 4 is an elevational view of a corner of my improved case, showing the manner in

which the short lapping end, which is usually placed inside, is crimped outside and made into a vertical rib, as indicated on the drawings.

Fig. 5 is a plan view of the parts shown in Figure 4 of the drawings.

Fig. 6 is an enlarged view of the intersection between the rib in the lid and a vertical partition which co-act together.

Fig. 7 is a plan view of the intersecting ribs on the case cover.

Fig. 8 is a perspective view of a portion of the case cover, showing the manner of constructing the corners.

Fig. 9 is a perspective view of a paper rib adapted to be applied to existing paper shipping cases.

Similar reference numerals refer to similar parts throughout the several figures of the drawings.

In carrying out this invention, and the manufacture of these improved cases, the lid, or cover, may be described as follows:

The lid is first blanked out from straw-board or similar material and is provided with the parallel score lines *a* and the outside score lines *b* and *c* respectively running crosswise of the blank and intersecting at the middle thereof. Where the score lines intersect a square opening 11 is punched out thereby permitting of the contracting of the blank along the score lines shown in Figure 7 to provide the ribs *R* as shown in Figure 2. When the ribs *R* are formed the opening 11 disappears; and also, due to the contracting of the blank to form the ribs, the flange portions 13 which form the edges of the lid may also be contracted to form the offset projections 13^a. To assist in holding the ribs *R* in proper form and also holding the projections 13^a together rivets or cleats 12 may be employed.

The ends of the top are formed as shown in Figure 8 wherein the end flanges 14 are turned inwardly beneath the side flanges 13 and held by rivets 15.

The part *B* of the box is also formed from a blank in such manner that the sides 17 may be formed at their ends with the offset ribs 19 which overlap the sides 17^a of the box as clearly shown in Figure 5, thereby providing vertical stiffening and spacing ribs 19 at the corners of the box body.

The interior of the box may be provided with suitable partitions 16 which cooperate

with the ribs R to assist in supporting the lid and also divide the interior of the box into separate compartments.

The sides of the box B as well as the top 5 10 may be provided with ventilating openings 18.

This construction, together with the construction of the lid, prevents in a very practical way, the packing of shipping cases 10 such that the ventilating holes 18 are closed.

The lid construction of this case permits of two (2) very important features being carried out; first, the shipping cases must be securely tied, and to this end the 15 construction is well designed to permit a shipping twine to be placed over the box lid in either direction, closing in the center of the box where the longitudinal and transverse ribs are cut. The twine by which the 20 lid is secured to the box lays flat on the surface of the lid and thus eliminates the usual practice of picking boxes up by the string or tying cord, thus causing the boxes to tilt and making the chickens or other 25 contents slide to one end or side. When chickens are shipped and are crowded in one end or corner of the box by tilting the same they become trampled and crowded to such an extent that they are frequently injured or die from suffocation; and second, the rib through the center of the lid provides adequate means for attaching lifting 30 means, such as, a hand loop 20 which is adapted to be secured to the rib R on the lid.

The partition 16, shown on Figure 1, and

Figure 6, of the drawings, is provided with a right angled flange 22 adapted to be secured to the sides of the case by rivets or other fastening means as shown in Figure 40 45 of the drawings. The usual ventilating holes are placed in the sides and ends of the case body as well as in the top of the lid and in each partition.

I claim:

1. In a crate for shipping live chicks, the combination of a receptacle body having openings and a cover therefor, said cover comprising upstanding rib members crossing at the central portion thereof and providing interior grooves, and partitions of greater height than the side of the receptacle body adapted to engage in said grooves thereby to divide the receptacle into a plurality of compartments. 55

2. In a crate for shipping live chicks, the combination of a receptacle body having air circulating openings, vertical ribs offset from the side of said receptacle body, a cover for said receptacle body also having 60 openings, upstanding ribs formed in crossing relation at the longitudinal and transverse centers of the cover and providing corresponding grooves at the inner side of the cover, downturned flanges at the edges of the 65 cover formed with offset portions, and partition members of greater height than the sides of the receptacle body engaging said grooves thereby to divide the receptacle into a plurality of compartments.

JOSEPH W. PARKS.
